UNITED STATES PATENT OFFICE.

BLAINE JENKINS AND TOY C. HAYES, OF LEONA MINES, VIRGINIA.

DRILL.

1,185,803.

Specification of Letters Patent.

Patented June 6, 1916.

Application filed April 22, 1916. Serial No. 92,915.

To all whom it may concern:

Be it known that we, BLAINE JENKINS and TOY C. HAYES, citizens of the United States, residing at Leona Mines, in the county of Lee and State of Virginia, have invented certain new and useful Improvements in Drills, of which the following is a specification, reference being had to the accompanying drawings.

10 This invention relates to certain improvements in drills and has relation more particularly to a device of this general character especially designed and adapted for use by miners or the like; and it is an object of the invention to provide a drill having novel and improved means wherein removable bits are employed whereby the bits, when unduly worn or otherwise unsuited for use, may be readily and conveniently replaced.

15 The invention consists in the details of construction and in the combination and arrangement of the several parts of our improved drill whereby certain important advantages are attained and the device is rendered simpler, less expensive and otherwise more convenient and advantageous for use, all as will be hereinafter more fully set forth.

20 The novel features of the invention will hereinafter be definitely claimed.

In order that our invention may be the better understood, we will now proceed to describe the same with reference to the accompanying drawings, wherein—

25 Figure 1 is an elevational view with a portion broken away of a drill constructed in accordance with an embodiment of our invention; Fig. 2 is a transverse sectional view taken through the entering end of the drill and through the shanks of the bits; Fig. 3 is an elevational view, detached, of the split sleeve as herein embodied; and Fig. 4 is a fragmentary view in elevation 30 of the shank of a bit.

As disclosed in the accompanying drawings, 1 denotes an elongated twisted drill substantially of a type generally employed in mining operations and having its penetrating end substantially flat and provided with the inwardly directed sockets 2 preferably pyramidal in form and which are adapted to receive the pyramidal shanks 3 of the bits 4, said bits 4 being disposed lon-

gitudinally on a predetermined curvature, 55 as the necessities of practice may require. The penetrating end of the drill 1 at a point intermediate the sockets 2 is provided with an opening 5 intersecting the inner end portions of the sockets 2 and in which is 60 inserted the split sleeve or ferrule 6 produced on a predetermined taper and having its bore threaded to receive the shank of the screw member 7, whereby it will be perceived that the sleeve or ferrule 6 may be 65 expanded in order to be properly seated within the recesses or notches 8 produced in the adjacent faces of the shank 3 whereby the bits 4 may be conveniently and effectively maintained in applied position. It 70 will be self-evident that when it is desired to remove a bit 4, it is only necessary to remove the screw member 7.

By constructing a drill in accordance with an embodiment of our invention, it will be 75 at once self-evident that the drill 1 proper may be produced of a cheaper grade of material as it is only essential that the bits 4 be made of high grade steel or the like.

From the foregoing description, it is 80 thought to be obvious that a drill constructed in accordance with our invention is of an extremely simple and comparatively inexpensive nature and is particularly well adapted for use by reason of the convenience 85 and facility with which it may be assembled, and it will also be obvious that our invention is susceptible of some change and modification without material departure from the principles and spirit thereof and 90 for this reason we do not wish to be understood as limiting ourselves to the precise arrangement and formation of the several parts herein shown in carrying out our invention in practice. 95

We claim:

1. In combination with a drill having its entering end provided with a socket and having an opening disposed therethrough intersecting the socket, an expandable member disposed through the opening, means for expanding said member, and a bit having a shank insertible within the socket, said shank being provided with a recess to receive the expandable member. 100

2. In combination with a drill having a socket in its entering end and having an opening disposed therethrough intersecting 105

2
said socket, a split tapered sleeve disposed through said opening, a screw engageable within the bore of the sleeve for expanding the same, and a bit provided with a shank 5 insertible within the socket of the drill, said shank being provided with a recess to receive the sleeve when expanded.

In testimony whereof we hereunto affix

our signatures in the presence of two witnesses.

BLAINE JENKINS.
TOY C. HAYES.

Witnesses:

ARTHUR RAY,
ROBERT B. McCULLOCK.
